[57] **CLAIM**

The ornamental design for a whirlpool jet nozzle for bathtubs and the like, as shown and described.

DESCRIPTION

FIG. 1 is an isometric view of a whirlpool jet nozzle for bathtubs and the like embodying my new design;
FIG. 2 is a side elevational view thereof, the opposite side being a mirror image of the side shown;
FIG. 3 is a top plan view thereof;
FIG. 4 is a bottom plan view thereof;
FIG. 5 is a front elevational view thereof;
FIG. 6 is a rear elevational view thereof.

FIG. 1.

FIG. 2.

FIG. 5.

FIG. 3.

FIG. 6.

FIG. 4.
